[57] CLAIM

The ornamental design for a combined portable radio, cassette and compact disc player, as shown and described.

DESCRIPTION

FIG. 1 is a front elevational view of a combined portable radio, cassette and compact disc player showing my new design;

FIG. 2 is a top plan view thereof, showing rear doors in an open position;

FIG. 3 is a rear elevational view thereof;

FIG. 4 is a rear elevational view thereof, showing the doors in an open position;

FIG. 5 is a right side view thereof, showing one door in an open position;

FIG. 6 is a left side view thereof, showing the opposite door in an open position;

FIG. 7 is a bottom view thereof, showing the doors in an open position; and,

FIG. 8 is a rear perspective view of an alternative embodiment, showing the doors in an open position. The views of the front, bottom and left side are the same as the corresponding views of the first embodiment.
